UNITED STATES PATENT OFFICE.

YOSHINAO KAWAKITA, OF KAMOTO-GUN, KUMAMOTO-KEN, JAPAN, ASSIGNOR OF ONE-
THIRD TO ISUKE SENOO, OF OKUBO-MACHI, JAPAN, AND ONE-THIRD TO EIJIRO
KONO, OF USHIGOME

ELECTROTHERAPEUTIC APPARATUS.

1,278,675.

Specification of Letters Patent. Patented Sept. 10, 1918.

Application filed November 24, 1916. Serial No. 133,124.

To all whom it may concern:

Be it known that I, YOSHINAO KAWAKITA, a subject of the Empire of Japan, residing at 179 Uekimachi, Kamoto-gun, Kumamoto-ken, Japan, have invented certain new and useful Electrotherapeutic Apparatus, of which the following is a specification.

This invention relates to electro-therapeutic apparatus.

10 The object of my invention is to provide an apparatus wherein a current of very high frequency and voltage and a second current of comparatively low frequency and voltage are caused to flow in an "operating" circuit 15 at the same or different times without causing short circuit, whereby joint or alternate application may be made to a patient according to the symptoms of the disease.

20 The accompanying drawing shows an example of the circuits according to the invention.

25 In my invention, the arrangement of circuit whereby the high frequency, high tension current, produced by the discharging action of a condenser, flows through a human body, is the same as the one commonly known as "diathermie", and may be described briefly as follows with reference to the drawing:

30 A primary circuit 1 which may be connected with a suitable alternating current source includes the primary coil 2₁ of a transformer 2, and the secondary coil 2₂ of the latter forms part of a circuit 3 which is 35 provided with a discharging gap 4, a condenser 5 and a primary coil 6₁ for inducing current in a further circuit 7. A secondary coil 6₂ corresponding to the primary coil 6₁ forms part of the circuit 7, which also includes a condenser 9, and two contacts 10, 10 which are to be applied to the human body to be treated so as to cause an oscillatory current of very high frequency to flow through the part affected. In order to obtain a brush-like discharge, when required, it is convenient to provide an induction coil 8 arranged concentrically to the secondary coil 6₂, and a discharging brush 11 in the circuit of the secondary coil 8. When using

this device the upper one of the contacts 10, 50 10 is led to the earth, and the brush 11 is held close to the part requiring the medical treatment.

55 The essential points of this invention are as follows:

A circuit 12₂ is provided branching out from the two poles of the condenser 9, and includes the secondary coil 13₂ of a small induction coil 13 with a movable iron core 13₃, and the primary coil 13₁ of said induction coil forms part of a circuit 12₁ which includes an interrupter 14, a commutator 18 hereinafter described, the coil 2₁ and a switch 15 for opening and closing the circuit. A branch circuit 16 provided with a heating 65 element may also be arranged as shown for the treatment of the patient by heat.

The above-mentioned commutator comprises a lever-shaped member 18₁ oscillating on an axis 17 as its center, its two arms being 70 insulated from each other, and respectively arranged to touch the contact points 19₂ and 19₁ or 20. The inner ends of said arms are respectively connected with the secondary coil 2₂ and the primary coil 2₁ of the 75 transformer 2. The contact point 19₁ is connected through a conductor 21, with contact point 20, and said contact point 20 with the circuit 1, and the contact point 19₂ is connected to the circuit 3. The point at which the circuit 12₁ connects with the primary coil 2₁ of the transformer 2 may be regulated. The contacts 19₂, 19₁, and 20 are so arranged that when the right-hand arm of the commutator 18 touches the contact point 19₁ the 85 other arm will touch the contact point 19₂, and when the former touches the contact point 20, the latter will move off of the contact point 19₂. The contact point 19₂ is preferably elongated as shown in the drawing, so that when the commutator is being moved over from the position shown the circuit 1 is opened before the circuit 3.

If the commutator is positioned as indicated in the drawing, the circuit 1 is closed 90 through the arm 18₁, contact point 19₁, conductor 21 and contact point 20, and the circuit 3 is also closed through the other arm

- 18₁ and contact point 19₂ with the result that an oscillatory current of very high frequency will be set up in the circuit 7. If at this time the switch 15 in the circuit 12₁ is open and the heating element 16 cut out or removed, the induction coil 13 produces no action and consequently only a very high frequency current of high tension will exist in the circuit 7. But if the switch 15 is closed, a current will flow from the primary coil 2₁ of the transformer into the circuit 12₁ in parallel with the circuit 1 and rejoin the latter at the contact 20 as will be readily traced on the drawing. Such current will pass through the primary coil 13₁ and induce a current in the secondary coil 13₂ of the induction coil 13, and consequently there will be two currents induced in the circuit 7. The high frequency, high tension, current produced by the coil 6₁ and the comparatively low frequency, low tension current produced by the coil 13₁ are quite different in their nature, that is to say, the former only flows with difficulty through a coil having self induction, and the latter will not flow through a condenser. Thus, in the present apparatus, the high frequency current will close its circuit only through the condenser 9 regardless of the circuit 12₂ and the current from the coil 13₂ will flow through all parts of the circuit 7, without short circuiting through the condenser 9. Accordingly both currents will flow into the circuit 7 (which includes the human body under treatment) without interfering with one another.
- If the right-hand arm 18₁ of the commutator 18 is now moved to the contact point 20, the other arm 18₁ moves away from the contact point 19₂ and the circuit 3 is opened but the other circuits remain closed, with the result that only the current due to the induction coil 13 will flow in the circuit 7. With the parts thus connected the circuit 1 may, of course, be regulated by the operation of an auto-transformer, or the current in the circuit 12₁ by moving the iron core 13₃ of the induction coil 13. As mentioned above, this invention is characterized by the fact that the two different kinds of current are, at the same or at different times, made to flow through what might be termed the "operating" circuit viz: the circuit 7 which includes the body of the patient. The high frequency current obtainable by the action of the coil 6₁ mainly raises the temperature of the human body and gently operates on cells of human body but it does not give any electric shock to the nerves when said current flows through the body. Thus such electric current has a bactericidal effect for medical treatment. The current derived from the induction coil 13 chiefly acts on the nerves and has as its main effect the cure of fatigue of the human body. Therefore,

if both of said currents be applied simultaneously, there may be many cases wherein remarkable electrotherapeutic effects may be obtained. It is uneconomical to provide both of these arrangements separately, and even if both be provided separately but in a single apparatus, it requires a large number of regulators, switches, etc., and it is troublesome in practice. In my apparatus, the comparatively low frequency, low tension circuit branches out from the two poles of the condenser inserted in the "operating" circuit, and the two kinds of electric current may be used together so as to suit the requirements of the patient without causing short circuit and thus the arrangement of circuits may be made very simple. Besides, as the two currents can be applied at the same or different time, it is very easy to handle the apparatus and various effects in the medical treatment will be obtained.

Having thus described my invention, what I claim and desire to secure by Letters Patent is:

1. In an electro-therapeutic apparatus the combination of a portion of a circuit having terminals adapted to be applied to the body of the patient, means for producing a very high frequency, high tension current in said circuit which includes a condenser, an induction coil the secondary coil of which is connected to the two poles of said condenser, and a main current supply which feeds the primary coil of said induction coil and also provides the current for inducing the said high frequency, high tension current.

2. In an electro-therapeutic apparatus the combination of a portion of a circuit having terminals adapted to be applied to the body of the patient, means for producing a very high frequency, high tension current in said circuit which includes a condenser, an induction coil the secondary coil of which is connected to the two poles of said condenser, a main current supply which feeds the primary coil of said induction coil and also provides the current for inducing the said high frequency, high tension current, a switch for controlling the flow of current from the main current supply to the primary coil of said induction coil, and a commutator for controlling the action of the main current supply upon the first mentioned circuit.

3. In an electro-therapeutic apparatus the combination of a portion of a circuit having terminals adapted to be applied to the body of the patient, a condenser and the secondary coil of a transformer; a second circuit including the primary coil of said transformer, a spark gap and the secondary coil of a second transformer; a second condenser connected across the ends of the latter secondary coil; a main supply circuit including the primary coil of said second transformer; an

induction coil the secondary coil of which is connected to the two poles of the first-mentioned condenser; a circuit including the primary coil of said induction coil and receiving current from said main current supply; a switch in the last-mentioned circuit; and a commutator in said second circuit.

In testimony whereof I have affixed my signature in presence of two witnesses.

YOSHINAO KAWAKITA.
